PAIR OF SPECTACLES

Joseph R. Watkins, Dover, N. J., assignor to Foster
Grant Co., Inc., Leominster, Mass., a corporation of Massachusetts

Application April 4, 1950, Serial No. 8,957

Term of patent 14 years

(Cl. D57—1)

To all whom it may concern:

Be it known that I, Joseph R. Watkins, a citizen of the United States, residing at Dover, Morris County, State of New Jersey, have invented a new, original, and ornamental Design for a Pair of Spectacles, of which the following is a specification, reference being had to the accompanying drawings, forming part thereof, in which:

Fig. 1 is a front view of a pair of spectacles showing my new design; and

Fig. 2 is a top plan view thereof.

The essential features of the design are shown in full lines.

I claim:

The ornamental design for a pair of spectacles, substantially as shown and described.

JOSEPH R. WATKINS.
